CLAIM

The ornamental design for a chainsaw carrying case, as shown and described.

DESCRIPTION

FIG. 1 is a perspective front view of a chainsaw carrying case.

FIG. 2 is a front view of the chainsaw carrying case of FIG. 1.

FIG. 3 is a rear view of the chainsaw carrying case of FIG. 1.

FIG. 4 is a right side view of the chainsaw carrying case of FIG. 1.

FIG. 5 is a left side view of the chainsaw carrying case of FIG. 1.

FIG. 6 is a top view of the chainsaw carrying case of FIG. 1; and,

FIG. 7 is a bottom view of the chainsaw carrying case of FIG. 1.

The broken line showing of portions of the carrying case is included for the purpose of illustrating environment and forms no part of the claimed design.

1 Claim, 7 Drawing Sheets
